UNITED STATES PATENT OFFICE.

CLARENCE O. FLOWERS, OF FLINT, MICHIGAN.

DUMPING-CAR.

1,271,303.

Specification of Letters Patent.

Patented July 2, 1918.

Application filed July 17, 1917. Serial No. 181,118.

To all whom it may concern:

Be it known that I, CLARENCE O. FLOWERS, a citizen of the United States, residing at Flint, in the county of Genesee and State of Michigan, have invented new and useful Improvements in Dumping-Cars, of which the following is a specification.

This invention relates to dumping cars, and more especially to those provided with a hopper bottom; and the object of the same is to produce an improved tram car for use on overhead tracks in carrying coal, ore, and the like—the same intended to coact with a peculiar tripper mechanism located at the point where dumping is to occur automatically and capable of being set at will to dump the car or not as desired.

Details of the invention will be found in the following specification, reference being had to the accompanying drawings wherein:

Figure 1 is a side elevation of this entire structure showing the gate closed in full lines and as contacting with the tripper to open it, and illustrating the gate in dotted lines as opened.

Fig. 2 is an end view, with the track or tracks partly in section.

The tram or freight car is designated broadly by the reference letter C. It has wheels W traveling on a pair of elevated rails E constituting an overhead track which we will assume leads from the point of loading to the point where the dumping is to occur. Overlying these rails are guard rails G at a point about where dumping is to occur, and the wheels W pass under these so as to hold them reliably on the rails E in a manner which is clearly understood. The motive power for the car is here shown as ropes or cables R, but this is not essential.

The shape of the body of the car is also immaterial excepting for the details herein-after described.

Coming now to the present invention, the bottom of the car is formed in the shape of a hopper, including downwardly converging walls 1 leading to a mouth or chute 2 beneath the midlength of the car-body, so that the coal, ore, or other granular material therein will rest normally on the walls of the hopper and within the chute, and will run out the latter when it is opened at its lower end. Normally it is closed by a gate herein designated by the numeral 3 and slightly curved as shown. The curve is part of a circle

struck around pivot points 4 on opposite sides of the hopper and from these points bars 5 depend and are inturned at their lower ends into feet 6 underlying and supporting the gate. Said bars 5 form pivotal supports or hangers for the gate, and the latter stands normally beneath the lower extremity of the chute and closes it as illustrated in full lines in Fig. 1. When the gate is swung aside on its hangers as indicated in dotted lines in this view, the mouth of the chute is open, but normally it is closed and the hangers rest against stops 7, the gate being held in closed position against accidental movement by the weight of the load within the chute 2. The rails E will be spaced so that the hopper and chute travel between them as will be clearly understood.

Let us assume for sake of illustration that each of the cars described above is loaded within or at the mouth of a mine, with coal; is drawn thence by the propelling means R along a considerable stretch of track and finally onto elevated rails E, led over a coal pile or dump, or perhaps over a spur or siding of the railway onto which freight cars are run and which are to be loaded by dumping into them the contents of these overhead tram cars C. It will be clear of course that all of the dumping must not occur at one point. If the coal is to be placed in a pile or a bin, or loaded into several cars of a coal train, the dumping must occur at selected points along the length of the overhead stretch of rails E. Therefore it is my intention to provide means for tripping or opening the gate 3 of each car wherever the load within said car is needed, but I have shown only one tripping mechanism in Fig. 1.

Each hanger 5 carries at its outer side a roller 10 adapted, in the movement of the car in the direction of the arrow shown in Fig. 1, to strike a tripper bar 11 when the latter stands in its path, and by the continued movement of the car C to be raised to the position shown in dotted lines and thereby to open the gate and dump the load. Said tripper is hinged as at 12 at its upper end to a track or runner 13, standing horizontal and extending along the line of movement of the car, and this runner is disposed at such elevation that when the gate swings to the open position, the rollers 10 may travel upon it. The lower end of the tripper bar 11 rests upon a support 14 which is at

a lower level than the runner 13, and accordingly the tripper stands oblique and in the direct path of the rollers 10 as the car advances. In such advance, the rollers 5 therefore strike the tripper bars and the hangers are swung upward and the gate swung open in a manner which will be clear, and after the gate has been opened and the car has proceeded along its course, the rollers 10 travel on the runners 13 so that the gate is held open for some little time. Therefore it is not necessary to check the movement of the car C. As soon as its gate is opened its load begins to dump out the mouth of the 15 chute 2, and this continues as long as the gate remains open and there is any load within the hopper—therefore the length of the runners 13 will be such as to permit the complete dumping of the load. In fact, in a 20 complete plant and where the elevated track E runs over a long bin or dump pile or railway spur, the runners 13 may be continuous excepting that they are interrupted at intervals by hinged tripper bars 11 wherever 25 it is expected that it may be desirable to dump a car. When not in use these tripper bars may be raised and held closed by buttons, locks, or suitable means not necessary to illustrate; but when any tripper bar is to 30 be used as a trip, it is dropped to the position illustrated in Fig. 1. This view may therefore be said to show only one unit or one dumping point within a considerable stretch of the complete system. The trippers 35 and runners will of course be spaced so that there is a clear passage between them for the pendant chute 2 as the car moves forward. I have spoken of the progress of this car as the dumping occurs, but it will be 40 possible if desired to check its progress and let it remain idle while the load runs out the chute. Probably this course would be followed if the tram car were depositing a load into a railway car beneath. Without further 45 illustration and description it is clear that devices might be provided for manipulating any pair of trippers from a remote

point, so that a proper operative could control the action of all those along the system, and therefore could dump any tram car at 50 the point desired. I do not wish to be limited to structural details, nor as to sizes, shapes and materials of parts.

What is claimed as new is:

1. The combination with overhead spaced 55 rails, a car traveling thereon and having a hopper bottom with a chute at its lowest point, a curved gate normally closing the mouth of said chute, hanger bars pivoted to the sides of said hopper at their upper ends, 60 and feet at their lower ends carrying the gate; of laterally projecting stop elements on said hangers near their lower ends, spaced rails beneath said elevated rails at the points where dumping is to occur and constituting 65 runners lying in a plane above the normal position of said elements, tripper bars hinged at their forward ends to said runners, and supports beneath said plane for holding the tripper bars inclined and in position to be struck by said elements, for the 70 purpose set forth.

2. The combination with overhead spaced rails, a car traveling thereon and having a hopper bottom with a chute at its lowest 75 point, a curved gate normally closing the mouth of said chute, and hanger bars pivoted to the sides of said hopper at their upper ends and connected at their lower ends with the ends of said gate; of rollers on the 80 outer side of said hanger bars near their lower ends, a pair of spaced tripper bars beneath said overhead rails where dumping is to occur, hinges supporting their forward ends in the direction of movement of 85 said car and at a level above the normal position of said rollers, and a stop supporting their other ends at a level below said normal position whereby when the tripper bars are thus set oblique the rollers strike 90 them and open the gate, as described.

In testimony whereof I affix my signature.

CLARENCE O. FLOWERS.
